STEEL SHEET PILE THREADER

Howard F. Caudill, Arlington Heights, Ill., assignor to Western Foundation Corporation, Chicago, Ill., a corporation of Delaware

Application November 3, 1949, Serial No. 125,345

4 Claims. (Cl. 61—63)

1

This invention is concerned with an improved apparatus for threading together adjacent individual sections of sheet metal piling preparatory to driving them into the ground.

More particularly, this invention is directed to a new and improved mechanical threading device for aligning interlocking edges of conventional sheet steel piling sections, so that mechanical threading or interlocking of adjacent pile sections is made possible.

In the construction of dams, levees, dikes, bridges, footings, docks, piers and like structures, it is often necessary to laterally support foundation beds against spreading under pressure, or to confine earth walls, water bearing strata, loose dirt or the like within lateral supporting structures. To meet such conditions, construction engineers have come to utilize sectional metal walls or pilings, usually of rolled steel sheets, so formed as to have mating or interlocking edges to prevent lateral creepage of the finished wall and to maintain maximum support from side pressures. The usual procedure in the construction of such a retaining structure is to insert these sheet sections or piles into the ground by means of a pile driver. After the first section is driven into the earth sand, or loose bed rock; the next section is raised either by the hoisting tackle of the pile driver or by a crane, and the interlocking edges of the two sections are placed in mating position by a man sitting astride the first section. The operator of the pile driver or crane then lowers the sheet pile and it is driven into the ground in interlocked relation with the first pile. The process is repeated until the wall is complete. As might well be imagined, the man who sits astride the previously driven piles and performs this mating or threading operation has an extremely difficult and dangerous job. The swinging sheets suspended by the crane are heavy, frequently weighing several thousand pounds and are liable to be swayed from side to side by the wind, often knocking the man attempting to thread the two sections together off of his precarious perch atop the driven sections, especially if the driven sections extend some distance above the ground.

It is the principal object of this invention to provide a new and improved mechanical apparatus for threading adjacent pile sections together, whereby the dangerous hand threading operation described above is eliminated.

It is a further object of this invention to provide a new and improved method of threading sheet piling together, which is safer, faster and

2

more positive in operation than previously known methods.

It is a still further object of this invention to provide a new and improved sheet pile threading apparatus completely operable and controllable by a man on the ground.

These and other objects will appear from time to time as the following specification and description proceed, and will more clearly be apparent with reference to the accompanying drawings in which:

Figure 1 is a front elevation of a threading device made in accordance with this invention, showing the device in operating position for threading adjacent pile sections together;

Figure 2 is a top plan view of the threading device shown in Figure 1 in its mounted position between two sheet piles;

Figure 3 is a right hand end view of the threading device;

Figure 4 is a left hand end view of the threading device showing the positioning and contour of the guide rollers;

Figure 5 is a schematic view illustrating the initial operating step and the relative positions of the piles in the threading method using this invention;

Figure 6 is a schematic view showing the new pile and the pile threader in their raised positions ready to effect threading between the new pile and the previously set pile; and

Figure 7 is a schematic view showing the new pile in aligned or threaded position ready to be lowered preparatory to driving the new section into the ground.

In Figure 1 I have illustrated fragmentarily a previously set pile designated P, and an un-driven pile designated P'. My improved threading apparatus is adapted to effect a clamping grip under or across the bottom edge of the un-driven pile, this bottom edge being designated e. This improved threading apparatus illustrated therein is comprised generally of a pair of draw bars 10, 10, with a bifurcated clamp 11 mounted thereon, a cam lever 12 attached between the draw bars to engage a cam plate 13 which contacts the clamp 11 and a guide roller 14 mounted for rotational movement near one end of each draw bar.

Each draw bar 10 may be cylindrical in shape with an eye 16 formed in one end for receiving a transversely positioned pin 17 on which the cam lever 12 is mounted between the two bars. The end of each draw bar opposite the eye 16 may be of a small diameter to receive the guide roller 14

which is rotatable thereon and is secured in its mounted position by any suitable means, such as a cotter key or pin 18, as shown in Figures 1, 2 and 4.

The bifurcated clamp 11 is adapted to grip the lower margin of a pile section having a female interlock edge 20, and may comprise identical mating front and back halves 21 and 22, respectively, adapted to grip the front and back faces of the pile section P. Since, as shown herein, the two halves of the clamp 11 are identical in structure, a description of the one-half will suffice for both.

The front half 21 as shown in Figs. 2, 3 and 4, comprises a rectangular metal back plate 23 to which are welded or otherwise secured a pair of vertical gripping fingers or rectangular metal plates designated generally at 24, 24 of Fig. 1. Each finger 24 includes a pair of parallel spaced, vertically extending metal finger bars 25. Each finger bar 25 is welded or otherwise fastened to back plate 23. Further each finger bar 25 is provided with a circular guide hole in its lower end for receiving one of the transversely extending draw bars 10 mounted for slidable movement therethrough. It will be recognized that cooperating pairs of finger bars 25 are registeringly aligned with one another and have their lower ends extending below the lower edge of the back plate 23. As thus mounted on the draw bars, the two clamp halves 21 and 22 may be firmly drawn toward one another for gripping a pile section P' by holding means comprising a pair of nuts and bolts 26, 26 disposed between the individual finger bars 25 of the clamp fingers 24 and reaching between the front and back halves 21 and 22 of the bifurcated clamp in its mounted position below the bottom edge e of the pile section P'. Washer plates 27 may be inserted beneath the nut and head of each bolt to prevent binding thereon on the spaced clamp finger bars 25. Each of two clamp halves further is provided, near its one lower end portion (as at the left hand end as seen in Figs. 1 and 2) with an L shaped end plate 28 and at its opposite end with a similar cam plate 13. The end plates and cam plates extend transversely inward of the back plates 23 of the two clamp halves to abuttingly meet when the clamp halves are drawn together in gripping a piling P'. Each of these plates are securely fastened to the back plates 23 of the clamp members 21 and 22, as by welding, and are adapted to receive and guide the draw bars 10 therethrough for sliding lateral movement. In operation, opposed adjacent edges of the end plates and cam plates will abut one another between the two clamp halves 22 and 23 to insure proper separation of the latter as the bolts and nuts 26 are tightened to draw the two clamp halves together in gripping a pile P'. Such a construction also insures proper separation of the rollers 14 so that they do not grip the grooves 35 of the driven pile P' so tightly as to bind therein and prevent their rolling movement therealong.

The cam lever 12 may be constructed with an enlarged cam end 30 provided with a cylindrical opening or eye 31 for receiving the pin 17 when mounted thereon. As shown in Figures 1, 2 and 3, the opening 31 is offset from the center of the enlarged end 30, thereby causing the cam lever to turn in an eccentric path about the pin 17. The periphery of the enlarged end 30 acts as a cam to contact the cam plates 13, and thereby move the bifurcated clamp 11 laterally along

the draw bars 10 when the lever is moved arcuately downward about the pin 17. The cam lever may be provided with a suitable opening 32 near its outer end for securing a lanyard 33 thereto.

Since the conventional sheet pile sections are not flat plates, but are rolled into bent channel contour, it is generally necessary to provide a contour bar 34 adapted to fit the contour of the 10 particular type of pile sheeting used, in order that the bifurcated clamp 11 may gain a solid purchase on the pile section P'. As illustrated in Figure 2, herein, the contour bar 34 is bent to fit the front contour of the pile section P' and is adapted to present a level clamping surface to the front half 21 of the bifurcated clamp 11. An additional contour bar may be used between the piling P' and the back half of the clamp if necessary.

20 The guide rollers 14 may be cylindrical wheels with beveled rims adapted to mate with grooves or depressions 35, 35 formed along both sides of a male interlock edge 36 extending along one 25 margin of a conventional driven pile section P, as seen in Figures 1 and 2. When the bifurcated clamp is properly mounted along the bottom left hand margin of a pile section P' by the bolts 26, as explained above, the guide rollers will rest in the interlock grooves 35 on either side of the 30 interlock edge 36 of the previously driven pile section P, to guide the pile P' during its upward travel, as will appear more clearly hereinafter under the operational description.

Use and operation

35 The operational steps for threading adjacent pile sections together by means of this apparatus are shown schematically in Figures 5, 6 and 7 of the drawings. It will be noted from these 40 figures that the initial operation for threading a new pile section P' onto a previously driven section P consists in swinging a new pile P' into the position shown in Figure 5, with the mating interlocking edges 20 and 36 approximately edge to edge. In this position the threader may be 45 mounted on the hanging pile P' near its lower left hand corner by means of the tightening bolts 26, so that the draw bars lie below and parallel to the lower trailing edge e of the pile P' with 50 the guide rollers 14 resting in the front and back interlock grooves 35 of the driven pile section P. Thusly, mounted between the two pile sections, with the cam lever 12 in a raised position, as 55 shown in Figure 1, the threader guides the pile section P' as it is pulled upwardly by a suitable crane or by the hoisting tackle of the pile driver. When the pile sections reach the relative positions shown in Figure 6 where the trailing edge of the pile P' is just above the top of the previously 60 driven pile P, the cam lever is pulled downwardly by the lanyard 33. As the lanyard pulls the cam lever 12 downwardly, the cam end 30 pushes against the cam plates 13 to force the bifurcated clamp 11 attached to the pile section 65 P' to the left along the draw bars 10 until the mating interlocking edges of the piles P' and P are in registering relation with one another, as shown in Figure 7. The pile P' is then lowered to cause the interlocking edges 20 and 36 to 70 mate as they are threaded together. When the pile P' is lowered a sufficient distance, such as to the initial loading position shown in Figure 5, the threader may be removed by loosening the bolts 26 to separate the two halves sufficiently to 75 allow removal of the rollers 14 from the grooves

35 of the driven pile P and the pile P' may then be further lowered and driven into the ground. This process repeats itself until the desired retaining wall is completed. It should be noted that by use of this method it is not necessary for a man to thread the pile sections together by hand, which is especially dangerous if the driven piles extend up to the air any great distance, since the lanyard operated threader illustrated herein is capable of operation from the ground level.

While I have herein shown and illustrated one form in which my invention may appear, it will be readily perceived that numerous changes, modifications and the substitution of equivalents may be employed without departing from the spirit and scope of this invention, and, therefore, I do not wish to be limited to the specific embodiment illustrated herein, except as may appear in the following appended claims.

I claim:

1. In an apparatus for threading together adjacent steel pile sections of the type having male and female interlocking edges, adjustable clamping means adapted to grip the lower marginal portion of a suspended steel pile, draw bar means inserted through the lower portions of said clamping means, guide rollers mounted at one end of each of said draw bars, a cam lever mounted for vertical arcuate movement about a pivot pin extending between said bars, cam means operably associated with said cam lever for moving said clamping means laterally along said draw bars, and lanyard means operable from the ground level for actuating said cam lever and cam.

2. In an apparatus for threading together adjacent steel pile sections of the type having male and female interlocking edges, adjustable clamping means adapted to grip the lower marginal portion of a suspended steel pile, draw bar means inserted through the lower portions of said clamping means, guide rollers mounted at one end of said draw bars and adapted to roll along grooves of said male interlocking margin, a cam lever mounted for vertical arcuate movement about a pivot pin extending between said bars, cam means operably associated with said cam lever for moving said clamping means laterally

6
along said draw bars, and lanyard means operable from the ground level for actuating said cam lever and cam.

3. In a mechanical apparatus for threading together adjacent sheet pile sections of the type having male and female interlocking lateral margins, clamping means for gripping the lower marginal portion of a piling section which is to be interlocked with a previously driven pile section, draw bar means inserted through the lower portions of said clamping means, guide rollers rotatably mounted on said bars for guiding said female interlocking margin of said pile section along said male interlocking margin of a previously driven pile section, a cam lever mounted for vertical arcuate movement about a transverse pin positioned between said bars, cam means operably associated with said cam lever and a lanyard for actuating said cam lever and cam whereby said male and female interlocking margins of adjacent pile sections are brought in mating relation with one another and said sections may be thereby threaded together.

4. An apparatus for interlockingly threading one edge of an undriven sheet pile with a mating edge of a previously driven sheet pile, comprising in combination, clamping means for gripping the lower end of said undriven pile, guide means for guiding said undriven pile along one vertical marginal edge of said previous driven pile, draw bar means slidably mounted through said clamp means and supporting said guide means thereon, and lever means operatively associated with said draw bar means and said clamp means for moving the latter along said bar means to bring one edge of said undriven pile into threading alignment with said mating edge of said previously driven pile.

HOWARD F. CAUDILL.
